Primary Examiner — Susan E Krakower*Assistant Examiner* — Andrew Kerr(74) *Attorney, Agent, or Firm* — Bishop, Diehl & Lee, Ltd.(57) **CLAIM**

The ornamental design for a lid for a beverage cartridge, as shown and described.

DESCRIPTION

FIG. 1 is rear perspective view of a lid for a beverage cartridge, showing our new design;

FIG. 2 is front perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings depict portions of the lid for a beverage cartridge that form no part of the claimed design. The dash-dot broken lines represent the boundary of the claimed design.
